DESIGN FOR AN ELECTRIC WELDING APPARATUS

Albert W. Baird, Cranford, N. J., assignor to The Linde Air Products Company, a corporation of Ohio

Application December 26, 1942, Serial No. 109,140

Term of patent 14 years

To all whom it may concern:

Be it known that I, Albert W. Baird, a citizen of the United States, residing at Cranford, in the county of Union and State of New Jersey, have invented a new, original, and ornamental Design for an Electric Welding Apparatus, of which the following is a specification, reference being had to the accompanying drawing, forming a part thereof.

In the drawing,

Fig. 1 is a front elevational view of an electric welding apparatus illustrating my new design; and

Fig. 2 is a right side elevational view of the electric welding apparatus illustrated in Fig. 1.

I claim:

The ornamental design for an electric welding apparatus, substantially as shown.

ALBERT W. BAIRD.
